UNITED STATES PATENT OFFICE.

EDWARD W. THOMPSON, OF LOWELL, MASSACHUSETTS.

TAG.

SPECIFICATION forming part of Letters Patent No. 291,813, dated January 8, 1884.

Application filed September 12, 1883. (No model.)

To all whom it may concern:

Be it known that I, EDWARD W. THOMPSON, a citizen of the United States, residing at Lowell, in the county of Middlesex and Commonwealth of Massachusetts, have invented certain new and useful Improvements in Tags, of which the following is a specification.

My invention relates more particularly to tags used in the postal service as direction-labels on sacks containing newspaper-mail, and is an improvement upon the patent granted me for tag for the same purpose, January 30, 1883, No. 271,378.

15 In the accompanying drawings, Figure 1 is an isometric view of a tag with my improvement attached. Fig. 2 is a side view of the same, the upper part being in section to show my improvement and the best method of attaching the same. Figs. 3 and 4 are modifications of my improvement, also shown in section. Figs. 2^A and 3^A are respectively cross-sections on the lines X X and Y Y.

A is a wooden tag, of the ordinary construction, with my improvement, as herein-after described. In place of the wooden tag with the hole bored in it, through which is passed a stout string, called "bull-twine," and that tied to the "puckering-string" of a 25 sack containing papers, I apply the following device: In the end of the tag I form a slot, B, cut vertically therein, the outer ends of the slot being slightly beveled. Through the arms formed by the slot B, I cut another 30 slot, C C', at right angles to the slot B, said slot preferably not extending to the end of the tag, and forming an orifice through each of the said arms. From the lower diagonally-opposite corners of the last-named slot I 35 cut grooves D D', terminating in holes at E E', said holes extending transversely through the tag.

F F' are springs, made of stout wire set into the grooves, the lower ends of said 45 springs being bent at right angles to enable them to be passed through the holes E E' in the tag, and they are then headed over a washer, G, or directly upon the wood. The upper ends of the springs F F' are bent into 50 overlapping spring-hooks H H', which pass through the orifices C C' from either side and beyond the sides of the slot B. The tops of the spring-hooks H H' present a bevel sufficient to receive the puckering-string I, which,

being pressed upon them, will force them 55 outward and apart, as shown by dotted lines in Fig. 2, and allow said cord to enter the slot B. To remove the tag from the puckering-string, to which it is directly attached, a loop of the string is passed over the top of 60 the spring-hooks H H' and forced into the slot B, whence it is readily withdrawn.

A modification of my improvement is shown in Fig. 3. Instead of two holes being made through the tag for the springs to pass 65 through, only one hole is bored diagonally from the bottom of the groove on one side of the tag to the bottom of the groove on the other side. The wire to form the springs in a single piece is then passed through the hole, 70 the hooks formed on the ends of the wire, and the springs forced into the grooves and through the orifice C C' into the position shown in Figs. 1 and 2.

In Fig. 4 is shown another modification of 75 my improvement, with the slot C C' extending to the ends of the arms formed by the slot B. Only one spring-hook may be used and the device still be operative, although, for greater strength and security in case of break- 80 age or accident to a single hook, it is preferable to use two.

The object of my improvement is to furnish a tag which shall be less expensive than my former invention, in which the springs 85 shall be protected and supported wherever strain is brought upon them, and so constructed that when the printed direction upon the tag shall become worn off or illegible the tag may be planed down and a new direction 90 printed thereon, and also in which, by the springs being set into grooves, said springs are better protected, the spring-hooks may be made shorter, greater strength secured, and the appearance of the tag improved. 95

I claim as my invention—

The combination of a tag slotted longitudinally and transversely, and provided with longitudinal grooves and transverse holes, and one or more spring-wires, each of said wires 100 being bent near one end into a hook, and near the other end bent at about right angles, and driven through one of said transverse holes and headed, as and for the purpose specified.

EDWARD W. THOMPSON.
